(57) **CLAIM**

The ornamental design for a golf club head, as shown and described.

DESCRIPTION

FIG 1 is a rear perspective view of a golf club head;

FIG. 2 is a top plan view thereof;

FIG. 3 is a bottom plan view thereof;

FIG. 4 is a heel end elevation view thereof;

FIG. 5 is a toe end elevational view thereof;

FIG. 6 is a rear elevational view thereof; and,

FIG. 7 is a front elevational view thereof.

The broken lines showing portions of the golf club head form no part of the claimed design.
